Primary Examiner — Catherine A Tuttle(74) *Attorney, Agent, or Firm* — Banner & Witcoff, Ltd.(57) **CLAIM**

The ornamental design for a trimmer, as shown and described.

DESCRIPTION

FIG. 1 is a front perspective view of a trimmer showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded area define the lower bounds of the claimed design and form no part thereof. The remainder of the broken lines are included for the purpose of illustrating the portions of the trimmer that form no part of the claimed design.
